DESIGN FOR A PIN TICKETING MACHINE

William Schrem, Elkins Park, Pa., assignor to
Soabar Company, Philadelphia, Pa., a corpora-
tion of Pennsylvania

Application April 5, 1946, Serial No. 128,307

Term of patent 14 years

(Cl. D55—1)

To all whom it may concern:

Be it known that I, William Schrem, a citizen of the United States, residing in Elkins Park, Montgomery County, Pennsylvania, have invented a new, original, and ornamental Design for a Pin Ticketing Machine, of which the following is a specification, reference being had to the accompanying drawing, forming part thereof, in which:

Fig. 1 is a front elevational view of a pin ticketing machine, showing my new design;

Fig. 2 is a left side elevational view of the machine;

Fig. 3 is a right side elevational view; and

Fig. 4 is a top plan view thereof.

I claim:

The ornamental design for a pin ticketing machine, substantially as shown.

WILLIAM SCHREM.
